US00D880574S

(12) **United States Design Patent** (10) **Patent No.:** **US D880,574 S**
(45) **Date of Patent:** **** Apr. 7, 2020**

(54) **GOGGLES**

(71) Applicant: **Guangzhou Jubao Sports Co., Ltd.,**
Guangzhou, Guangdong (CN)

(72) Inventor: **Chuanqing Liang**, Guangdong (CN)

(**) Term: **15 Years**

(21) Appl. No.: **29/660,849**

(22) Filed: **Aug. 23, 2018**

(51) **LOC (12) Cl. 16-06**

(52) **U.S. Cl.**

USPC **D16/312; D16/313**

(58) **Field of Classification Search**

USPC D16/300, 314, 312, 313

CPC A61F 9/02; G02C 3/003

See application file for complete search history.
